CLAIM

The ornamental designs for a vehicle grille, as shown and described.

DESCRIPTION

FIG. 1 is a perspective view of the vehicle grille;
FIG. 2 is a front view of the vehicle grille;
FIG. 3 is a left side view of the vehicle grille, where the right side view is substantially a mirror image of the left side view with the exception of the vehicle emblem depicted in broken lines;
FIG. 4 is a top view of the vehicle grille; and,
FIG. 5 is a bottom view of the vehicle grille.
The broken lines in the drawings depict portions of the vehicle grille that form no part of the claimed design.
